UNITED STATES PATENT OFFICE.

WILLIAM SHERMAN PHILLIPS, OF CAMERON, WEST VIRGINIA.

CHAIR.

958,529.

Specification of Letters Patent. Patented May 17, 1910.

Application filed May 14, 1909. Serial No. 495,960.

To all whom it may concern:

Be it known that I, WILLIAM SHERMAN PHILLIPS, a citizen of the United States, residing at Cameron, in the county of Marshall and State of West Virginia, have made certain new and useful Improvements in Chairs, of which the following is a specification.

My invention is an improvement in chairs, and consists in certain novel constructions, and combinations of parts hereinafter described and claimed.

The object of the invention is to provide a chair, which will fold up under a table or other support out of the way, when not in use, by means of a spring and which may be easily drawn out into position when required, and will be locked in such position by its own weight.

Referring to the drawings forming a part hereof: Figure 1 is an end view of a portion of a table provided with two chairs, Fig. 2 is a plan view of the telescoping arm, and its connections, Fig. 3 is a perspective view of the same, Fig. 4 is a side view, partly in section, of a portion of the chair, Fig. 5 is a similar view of the outer section of the telescoping arm, Fig. 6 is a plan view of the bracket, and Fig. 7 is a perspective view of the plate for connecting the bar to the table.

The embodiment of the invention shown in the drawings comprises a table, which may be of any preferred construction, and as shown in the drawings, consists of a top 1, supported by legs 2, and the table is provided near each side with the usual extension slide 3, having on its inner face the undercut groove 4. A bar 5 is provided near each end with a plate 6, connected to the bar by a bolt 7, which passes through registering openings in the bar and plate, and the free end of the bolt is engaged by a wing nut 8. The inner end of the plate is bent at a right angle to the plate as at 9 and engages the bar, while the other end is bent slightly toward the bar as at 10 and rests in the undercut groove as shown in Fig. 1. At approximately the center of the bar, a depending arm 11 is arranged perpendicular to the bar, and a bracket plate 12 is arranged on each side of the arm, each of said plates having at its upper end an angular portion 13, which is secured to the bar by rivets 14, and at its lower end an offset journal pin 15. A bearing 16 connected with a bracket is journaled on each pin, and secured in place by a nut 18.

The bracket consists of spaced plates 17, connected at each end by bolts 18, 19, and on one of the bolts 18 is journaled a pulley 20, and on the other is journaled, a bearing 21 on a hanger 22, connected with the outer section of a telescoping bar 23, provided with feet 24.

A link 25 is pivoted by one end to an eye 26 on the hanger, and the other end of the link is bent slightly as at 27, and provided with an opening in which is secured one end of a chain 28, and the other end is connected with a hook 29 on a coil spring 30, the chain passing over the pulley. The opposite end of the spring is also provided with a hook 31, which engages an eye 32 on the end of a threaded stem 34, which passes loosely through an angular bracket 33 on the adjacent bracket plate, and is engaged by a nut 35, to secure the stem in place, and to permit adjustment of the spring.

The telescoping bar before mentioned, consists of the outer section 23, and an inner section 36, to whose free end is connected a cross bar 37, which has at each end a vertical lug 38, provided with a bayonet slot 39.

The chair consists of a seat 40, supported by legs 41, which are braced by cross bars 42, and the seat is provided at its rear corners with lugs 43, to which are pivoted the side bars 44 of the back. The said side bars are longitudinally slotted at their lower ends, and a plate 45, is secured in the slot, and the plates and legs are provided with registering openings, through which pass the pivot pins 46. The lower face of the seat, adjacent to each side bar, is recessed as at 50, and a plate spring 51, is secured in each recess by screws 52, the free end of the spring extending beneath the lower end of the plate 45, before mentioned, and the said plate is provided with an enlarged lower end, having two flat faces 53 and 54, which rest against the plate, the face 53 when the back is erect and the face 54 when the back is folded. It will be evident, that the construction provides a means for locking the back in both erect and folded positions. The ends of the rear legs are provided with rollers or casters 47, and each front leg is provided with a foot 47^a and on its inner face, and near its lower end, with a plate 48, which is fitted upon and secured to the leg, and each of the plates is provided with an angular hook 49, for engaging the bayo-

net slot 39 of the adjacent lug 38, the chair swinging on the said hooks.

The operation of the device is extremely simple, and is as follows: When the chair is in the position shown at the right of Fig. 1, that is in folded position, and it is desired to unfold the same, the seat is grasped, and pulled outward. This swings the telescoping bar on the bolt 19, to bring the said bar into the horizontal position shown at the left of Fig. 1, and at the same time the chair swings on the hooks 49, into the position shown in the same figure. The back is now elevated, and the weight of the chair holds it in such position. To fold the chair beneath the table, the process is reversed, the back being first folded, and the chair being tilted backward, when the spring 30 will draw the parts into the folded position shown at the right of the same figure. The foot 47^a of the front legs, is of felt or like soft material, to permit the chair to fold noiselessly, and to prevent the marring of the table, by the engagement of the foot therewith.

It will be evident that the table may be provided with an indefinite number of chairs, from one to as many as may be desired, and each chair is entirely independent of all the others. The entire mechanism of the chair may be removed from the table, by loosening the wing nuts 8, and swinging the plates out of engagement with the undercut notches. The chairs are shown as arranged in pairs, and it is evident that the supporting bar or bracket may be secured to any suitable support, not necessarily a table, which is shown merely for convenience. It is also evident that by slight modification of the arm 11, three chairs might be supported thereby, and with no modifications whatever, four chairs could be connected therewith, one on each face of the said support. With small tables designed for four persons this would be the preferable arrangement.

It will be evident from an inspection of Fig. 1, that when folded, the chairs are entirely supported by the table, and do not touch the floor at any point, and that there is sufficient clearance beneath the lowest part of the chairs and the floor, to permit the use of a carpet sweeper or a like device, without interfering with the chairs.

The improved chair is especially adapted for use at telephone tables dining tables and writing desks, and may be made in any suitable style, or of any suitable and desired material. In folding the chair, it is rolled inwardly, on the rollers 47 while the front is tilted, and since there is no lifting of the chair, required to fold or unfold, it may be made of heavy material, without becoming unwieldy. It will also be evident from Fig. 1 that the spring does not act on

the telescoping bar as long as it is in the position shown at the left, except in the direction of the length of the link, and will not commence to exert a swinging action until the hanger is moved out of a true vertical position. This is due to the bent end of the link, and its connections with the hanger instead of to the bar.

By means of the telescoping arm, the chair may be adjusted toward and from the table to suit the user, and usually in folding the chair the arm is contracted before commencing the folding operation, the chair thus occupying less space under the table.

I claim:

1. The combination with a table provided on its under face with blocks spaced apart from each other, and provided on their adjacent faces with undercut grooves, of a bar provided at its center with a depending arm, a plate at each end of the bar and having an angular portion at one end for engaging the bar and an angular portion at the other end for engaging the slot, a bolt passing through the bar and the plate, and a nut on the bolt for securing the plate thereto, a bracket plate secured to each side of the arm and provided at its lower end with a journal pin, a pair of spaced plates on each side of the arm and provided with a bearing engaging the adjacent journal pin, a bolt at each end of the plates and connecting them together, a pulley on the upper bolt, a hanger journaled on the lower bolt, a telescoping arm whose one section is connected with the hanger, a cross bar secured by its center to the free end of the other section, and provided at each end with a vertical lug, having a bayonet slot, a chair comprising a bottom and legs, a folding back hinged to the bottom, a plate secured to the inner face of each front leg, an angular hook on the plate with which the bayonet slot of the adjacent lug engages, a link pivoted by one end to the section of the telescoping arm adjacent to the hanger, a chain connected with the other end, a bracket on the bracket plate, and a spring connected by one end to the bracket, and by the other to the chain, said chain passing over the pulley.

2. The combination with a table provided on its under face with blocks spaced apart from each other, each having on its inner face an undercut slot, of a bar provided with a central depending arm, a plate detachably connected with each end of the support and engaging the slot of the adjacent block, a pair of spaced plates journaled on a vertical axis, on the lower end of the arm and at each side thereof, a pulley journaled between the plates at their upper end, a hanger journaled between the plates at their lower end, a telescoping arm whose one sec-

tion is connected with the hanger, a link pivoted to the hanger, a chain connected with the free end of the link, a spring connected with the adjacent bracket plate and with the chain, and passing over the pulley, and a chair provided with a folding back pivoted to the outer end of the other section.

3. The combination with a table provided on its under face with blocks spaced apart from each other, each having on its inner face an undercut slot, of a bar provided with a central depending arm, a plate detachably connected with each end of the support and engaging the slot of the adjacent block, a pair of spaced plates journaled on a vertical axis, on the lower end of the arm and at each side thereof, a pulley journaled between the plates at their upper end, a hanger journaled between the plates at their lower end, a telescoping arm whose one section is connected with the hanger, a chain connecting the hanger with the bracket plate and passing over the pulley, a spring interposed in the chain, and a chair provided with a folding back hinged to the other section of the arm.

4. The combination with a table, of a bar provided with a central depending arm, means for detachably connecting the ends of the bar with the table, a hanger journaled on a transverse axis on the lower end of the arm, a telescoping arm whose one section is rigid with the hanger, a chair provided with a folding back pivoted to the other

section, and a spring connecting the hanger with the depending arm.

5. The combination with a table, of a depending arm detachably connected therewith, a hanger journaled in a transverse axis on the lower end of the arm, a telescoping arm whose one section is rigid with the hanger, a chair provided with a folding back pivoted to the other section, and a spring connecting the hanger with the depending arm.

6. In a device of the class described, an arm, means in connection with the arm for detachably connecting it with a support, a hanger journaled on a transverse axis on the lower end of the arm, a telescoping arm whose one section is rigid with the hanger, a chair provided with a folding back pivoted to the other section, and a spring connecting the hanger with the depending arm.

7. In a device of the class described, a central support provided with a plurality of vertically arranged journal pins spaced at equal angles with each other, a plurality of telescoping arms, a bracket for each arm, upon which one of the sections is hinged, each of said brackets having a bearing for engaging a journal pin, and a chair hinged to the other section of each arm.
